UNITED STATES PATENT OFFICE.

JOHN E. HUNSAKER, OF VIENNA, ILLINOIS, ASSIGNOR OF ONE-THIRD TO LUCAS PARKER AND ONE-THIRD TO RALPH MORRAY, BOTH OF VIENNA, ILLINOIS.

DESIGN FOR A CHART.

53,631.

Specification for Design.

Patented July 22, 1919.

Application filed March 5, 1919. Serial No. 280,868. Term of patent 7 years.

To all whom it may concern:

Be it known that I, JOHN E. HUNSAKER, a citizen of the United States, residing at Vienna, in the county of Johnson and State of Illinois, have invented a new, original, and ornamental Design for a Chart, of which the following is a specification, reference being had to the accompanying drawing, forming part thereof.

The figure is a face view of a chart, showing my new design.

What is claimed is:

The ornamental design for a chart, as shown in the accompanying drawing.

JNO. E. HUNSAKER.

Witnesses:

LUCAS PARKER,
RALPH MORRAY.
